MACHINE FOR SHAPING UPPERS OVER
LASTSCharles F. Pym, Beverly, Mass., assignor to
United Shoe Machinery Corporation, Paterson,
N. J., a corporation of New Jersey

Application January 29, 1934, Serial No. 708,722

67 Claims. (Cl. 12—7)

This invention relates to machines for use in the manufacture of shoes and in some aspects more particularly to machines for shaping uppers over lasts. The invention is herein shown as embodied in a machine for lasting the sides of shoes between their toe and heel-end portions, and adapted more particularly for operation upon shoes in which the upper in the lasting operation is secured to the insole by adhesion, but it will be recognized that in many of its novel features the invention is not limited to the manufacture of that type of shoe or limited in respect to the portion of the shoe upon which the operation is performed.

Important features of the invention are to be recognized in a novel combination of means for conforming an upper tightly to the contour of its last and for pulling its marginal portion inwardly over an insole on the last without any substantial pressure of the upper against the insole and then pressing its marginal portion upon the insole while under pulling strain and wiping it inwardly over the insole. Thus the danger of any slackening of the upper on its last after the upper-pulling operation is avoided and in the manufacture of a shoe the margin of the upper of which is secured to the insole by adhesion substantial insurance is afforded that the insole will not be wrinkled or otherwise displaced in the overwiping operation and that the margin of the upper will not be pressed into premature adherence to the insole. In one important aspect the invention provides for thus operating upon the upper along the shank and forepart of the shoe. As herein shown the machine is provided with upper-pulling means comprising grippers arranged to operate at the ball and shank portions of the shoe and movable inwardly over the shoe bottom to tighten the upper over its last and to draw its marginal portion inwardly over the insole, overlaying members or wipers movable with said grippers and arranged to extend along the opposite sides of the shoe between its toe and heel-end portions, and mechanism for effecting relative movement of the wipers and the shoe heightwise of the shoe to press the margin of the upper upon the insole after the margin of the upper has been drawn inwardly over the insole and while the upper is held under strain by the grippers, this mechanism being arranged thereafter in response to resistance of the shoe to the pressure applied to impart to the wipers movements farther inwardly over the insole in wiping engagement with the upper while applying progressively increasing pressure to the upper heightwise of the last to force it

into firm adherence to the insole. In accordance with a further feature the wipers are preferably heated, thus increasing the effectiveness of their action on the margin of the upper to smooth it free from wrinkles and to secure firm adhesion of the upper to the insole through hastening of the setting of the cement.

In the illustrated machine the shoe is supported yieldingly bottom downward with its bottom face located initially a predetermined distance above the upper-engaging faces of the wipers. A pair of abutments are provided for engaging the top of the heel end and the top of the forepart of the shoe and its last, to support the shoe against pressure applied on its bottom face, and means is provided, herein shown as a slide, for moving the shoe-supporting means toward the abutments to carry the shoe into engagement with the abutments and then to effect a depression of the shoe-supporting means relatively to the slide. The wipers are supported on the slide and are connected to supporting brackets by parallel links which are arranged to impart to the wipers their inward movements without varying their angular relation to the shoe bottom, spring means being provided for opposing the inward movements of the wipers and for thereafter moving them outwardly. In the construction shown, the grippers comprise movable jaws carried by the wipers and arranged to cooperate therewith to grip and pull the upper. The movable gripper jaws are located opposite each other along the shank portion of the shoe and at the opposite sides of the ball of the shoe, and in order that the gripper jaws may be moved relatively to the wipers to grip the upper before the wipers begin their inward movements, there is provided, in accordance with a further feature of the invention, mechanism operative in response to movement of the wiper support heightwise of the shoe to impart to the gripper jaws movements both heightwise and laterally of the shoe relatively to the wipers to clamp the opposite side portions of the margin of the upper against the wipers, this mechanism being operative thereafter to impart to the gripper jaws movements relatively to the wipers to release the upper in time relation to the inward movements of the wipers.

In order to determine the relation between the wipers and the shoe during the early part of the movement of the wipers and grippers inwardly over the insole, there is provided, in accordance with another feature of the invention, novel means for positioning the wipers heightwise of the shoe relatively to the bottom of the shoe.

This means, as herein shown, comprises gaging devices which as the wipers are moved heightwise of the shoe engage the wipers and thus cause the parallel links to impart to the wipers their inward movements against the resistance of said spring means, the movements of the wipers toward the shoe being thus limited by the gaging devices which are also adjustable heightwise of the shoe to determine the distance between the wipers and the bottom face of the insole. In order that the spring means will be effective to impart to the wipers movements heightwise of the shoe to press the margin of the upper upon the insole, the machine is also provided with means for releasing the wipers from the gaging devices at a predetermined time in the inward movements of the wipers and grippers. As illustrated, this means comprises a pair of rods carried by the above-mentioned slide and arranged to impart to the gaging devices in time relation to the inward movements of the grippers and wipers movements heightwise of the shoe to release the wipers to the action of the spring means. As the slide continues to move upwardly, the wipers are moved farther inwardly over the insole in wiping engagement with the upper by the parallel links against the increasing resistance of the spring means. In accordance with another feature, there is provided means for preventing outward return movement of the wipers, in the movement of the slide away from the abutments, until after the shoe-supporting means has been returned relatively to the slide to its initial position, the shoe being thus supported above the path of the outwardly moving wipers so as to avoid any possibility of displacement of the margin of the upper by outward drag of the wipers thereon.

The above and other features of the invention, including various novel details of construction and combinations of parts, will now be more particularly set forth by reference to the accompanying drawings and pointed out in the claims.

In the drawings,—

Fig. 1 is a view in front elevation of the upper left-hand portion of a machine in which the present invention is embodied;

Fig. 2 is a section on the line II—II of Fig. 1 showing the parts in their initial position;

Fig. 3 is a section on the line III—III of Fig. 1 but showing the positions of the parts at the beginning of the upper-pulling operation;

Fig. 4 is a view similar to Fig. 3 with the parts shown in the positions which they assume at the end of the upper-pulling operation;

Fig. 5 is a view similar to Fig. 3 showing the relation of the parts to the shoe at the completion of the overwiping operation;

Fig. 6 is a section on the line VI—VI of Fig. 1; and

Fig. 7 is a detailed plan view illustrating the construction of the wiper and wiper holder.

The invention is illustrated as applied to a machine organization which is in many respects similar to that illustrated in Letters Patent of the United States No. 1,549,243, granted on August 11, 1925, on an application filed in the name of E. E. Winkley with portions of the machine constructed as disclosed in Letters Patent of the United States No. 1,951,373, granted March 20, 1934, upon an application filed in my name, although it is to be understood that the invention is not limited to organizations of that particular character. Machines of the type illustrated in said Letters Patent are twin machines comprising

two sets of mechanisms whereby one shoe is subjected to pressure simultaneously with the release from pressure of another shoe previously operated upon. Only one of the two sets of mechanisms is herein illustrated or need be referred to for an understanding of the present invention. As more fully illustrated in the above-mentioned Letters Patent No. 1,549,243 the machine is provided with a pair of vertical rods 20 (Figs. 1 and 2) which support adjustably near their upper ends a cross-head 22. To this cross-head there are adjustably secured a toe post 24 and a heel post 26 which serve to support the shoe against upwardly directed pressure applied on its bottom face. The toe post 24 has a rubber-covered roll 28 thereon for engaging the shoe or last on the top of the forepart and the heel post is provided with a plate 30 arranged to engage the top face of the heel-end portion of the last, the plate 30 being mounted on a block 32 pivotally connected at 34 to the heel post and arranged to be swung about its pivot by an adjustable screw 36 against the action of a flat spring 38 to adjust the plate 30 so that it will bear evenly on the top face of the last, as more fully disclosed in my copending application referred to above.

Mounted on the rods 20 is a slide 40 to which upward and downward movements are imparted through a link 42 connected at 44 to the slide and operated by mechanism not herein shown in detail since it is fully disclosed in the Letters Patent No. 1,549,243 above mentioned. The slide 40 supports a box 46 provided with a pair of trunnions one of which is indicated at 48 in Fig. 1 mounted in bearings on the slide so that the box 46 may tip about an axis extending laterally of the shoe, the box being held normally in a predetermined position, determined by a spring-pressed plunger 50 carried by the box and engaging the slide, by a spring 52 connecting the slide and the box.

Vertically movable in the box 46 is a casting 54 supported by four springs 56 which are yieldable in response to resistance of the shoe to the pressure applied. Mounted in guideways on the casting 54 for movements in directions widthwise of the shoe is a slide 58 which is adjustable along its guideway by a screw 60 held against lengthwise movement by a lug 62 fast on the casting. Mounted in guideways on the slide 58 for movements in directions lengthwise of the shoe is a slide 64 which is adjustable along the guideways by a screw 66 held against lengthwise movement relatively to the slide 64 by a plate 68 fast on the slide 64, the screw being threaded in a lug 70 on the slide 58 and having a hand wheel 72 thereon for turning it. The slide 64 serves as a support for four brackets two of which are located opposite each other near the toe end of the shoe and the other two of which are located opposite each other near the heel end of the shoe. The brackets 74 near the toe end of the shoe are mounted in guideways on the slide 64 for movements laterally of the shoe and are adjustable toward or from each other by a shaft 76 having right and left-hand threads thereon engaging lugs on the brackets and a hand-wheel 78 secured to its outer end for turning it, the shaft 76 being held against lengthwise movement relatively to the slide 64 by spaced projections 80 on the slide engaging shoulders 82 on the shaft. The brackets 84 (Fig. 6) at the heel end of the shoe are pivotally connected to the slide 64 by shouldered studs 86. The brackets 74, 84 have connected thereto respectively by par-

allel links 88, 90 angularly shaped holders 92, 94 and each pair of holders 92, 94 serve to support one of a pair of ironing members or wipers 96, 98. The wipers 96, 98 extend along the opposite sides of the shoe (Fig. 1), and are shaped both heightwise and widthwise of the shoe to conform substantially to the curvatures of the opposite edges of the shoe bottom. The wipers 96, 98 are positioned on the holders 94 by dowel pins 100 which extend upwardly into recesses formed in the wipers, and on the holders 92 by pins 102 extending upwardly into lengthwise slots 104 formed in the wipers, the wipers being provided also with convex projections 106 (Fig. 7), arranged to engage complementally shaped recesses 108 formed in the holders 92. It will be seen that rotation of the hand wheel 78 moves the brackets 74 toward or from each other and that this movement of the brackets 74 through the wipers 96, 98 causes the brackets 84 to swing about their pivotal connections to the slide 64. The portions of the wipers near the toe end of the shoe are thus moved greater distances toward or from each other than the portions of the wipers near the shank of the shoe. Since variations in widths of shoes of different sizes are greater at the forepart than at the shank of the shoe, the wipers 96, 98 may accordingly be adjusted to take care of a number of shoes of different sizes, although for wide variations in sizes, as well as for variations in styles, differently formed wipers will be substituted.

One of each pair of parallel links supporting the holders 92, 94, on the brackets 74, 84, namely, the link 88, has an extension 110 to the outer end of which is pivotally connected a rod 112. Mounted on each rod 112 is a bushing 114 which is held against a shoulder 116 on the rod by a compression spring 118 surrounding the rod and engaging at its lower end a washer 120 supported by a nut 122 threaded on the rod, Fig. 2. Surrounding the bushing 114 and bearing at its lower end against a flange 124 on the bushing and at its upper end against a flange 126 formed on a second bushing 128 slidably mounted on the rod 112, above the shoulder 116, is a compression spring 130 which is of less capacity than the spring 118. Each bracket 74, 84, has a laterally extending forked arm 132 which partially surrounds the bushing 128 and is provided with recesses 134 arranged to receive trunnions 136 on the bushing 128, the construction being such that the springs 130 maintain the holders 92, 94, initially in upraised positions (Fig. 2), in which their outer side faces are against the upwardly extending portions of the brackets 74, 84. It will be seen that when the parallel links 88, 90 are swung about their pivots, by means hereinafter described, to impart inward movements to the wipers 96, 98, the springs 130 are compressed until the bushings 114 engage the bushings 128, after which continued swinging of the links 88, 90 acts to compress the stronger springs 118.

In the illustrated machine the shoe is supported initially bottom downward by a member 138 which, as shown in Figs. 1 and 3, engages the heel-seat portion of the shoe, and a member 140 arranged to engage the bottom face of the insole substantially midway between the opposite sides of the shoe just rearwardly of the toe end of the shoe as shown in Figs. 1 and 2. The member 138 is mounted for sliding movements in directions heightwise of the shoe in a guideway formed in an upwardly extending arm 142 of a standard 144 secured to the casting 54. The arm

142 is provided with a shoulder 146 and projecting from the shoulder is a pin 148 which acts to centralize a compression spring 150 with a recess 152 formed in the member 138. The spring 150 bears at its lower end against the shoulder 146 and at its upper end against the member 138 at the upper end of the recess 152. A projection 154 on the arm 142 is arranged to engage a stop 156 on the member 138 and to limit the upward movement of the member 138 under the action of the spring 150. The forepart supporting member 140 is slidably mounted for movements in directions heightwise of the shoe in a guideway formed in a standard 158 secured to the slide 64 (Figs. 1 and 2) and is upheld with a projection 160 on the member 140 engaging a stop 162 on the standard by a compression spring 164 which bears at its lower end against the slide 64 and at its upper end against the member 140 at the upper end of a recess 166 formed in the member. The stops 156, 162 are so located that when the parts are in the positions shown in Figs. 1 and 2 the shoe is supported by the members 138, 140 with its bottom face a predetermined distance above the upper-engaging faces of the wipers 96, 98. In the upward movement of the slide 40, the shoe and last are carried into engagement with the members 28 and 30 by the supporting members 138 and 140 after which as the slide continues its upward movement the springs 150 and 164 are compressed, thus effecting a depression of the supporting members 138 and 140 relatively to the slide.

In order to hold the shoe on the supporting members 138, 140 and to determine the proper lateral position of the heel-end portion of the shoe, the illustrated machine is provided with gages 168, one of which is shown in Fig. 1, located opposite each other at the heel end. The gages 168 are substantially the same as similar mechanism shown and described in my copending application Serial No. 481,919 mentioned above, each gage comprising an arm 170 (Fig. 1), mounted on a block 172 for swinging movements laterally of the shoe and having a leather cover 174 thereon to contact with the shoe. The arms 170 are interconnected to swing in unison and are adjustable toward or from each other by a shaft 176 having right and left threads in engagement with blocks 180 that are swiveled on the outer ends of the respective arms, the shaft having a knurled head 182 thereon for turning it. The supporting block 172 is pivoted at 184 on the standard 144 to permit the arms 170 to be swung out of operative position to facilitate removal of the wipers 96, 98. A spring 186 connected to one of the arms 170 and to the standard 144 holds the arms normally in operative position, the arrangement of the spring in relation to the axis 184 being such that it will also maintain the arms in inoperative position when they are swung to that position.

The machine is provided with means for maintaining the wipers 96, 98 in a heated condition. For this purpose there is mounted in a recess in each end of each wiper 96, 98, an electrical heating unit 188. From each heating unit 188 electrical conductors 190 lead to any convenient source of electrical energy for heating it.

When the operator places the shoe on the supporting members 138, 140, the shoe is held against lateral tipping movements on these supports by the gages 168 which act also properly to position the heel end of the shoe laterally of the wipers. It is contemplated that the complementally shaped wipers 96, 98, will afford a sufficiently

definite indication of the lengthwise position of the shoe and that the operator, by swinging the toe end of the shoe, will locate the forepart in proper lateral position on the support 140. As the slide 40 moves upwardly the shoe and last are carried by the supports 138, 140 into engagement with the members 28, 30, and substantially at the time of such engagement upward movement of the wipers 96, 98 is limited by means which is arranged to determine the distance between the bottom face of the insole and the wipers as they begin their inward movements. By reference to Figs. 3, 4 and 5, it will be seen that each wiper 96, 98 has secured to it a bracket 192 which is arranged to engage, as the slide 40 moves upwardly, an abutment piece or stop 194 secured to a gaging member 196 which is slidably mounted on the rod 20. The gaging member 196 is supported on the rod by an adjustable collar 198 which is secured to the rod by a set screw 200. A heavy compression spring 202 surrounding the rod 20 and bearing at its lower end against the member 196 and at its upper end against the cross-head 22 acts to hold the member against its supporting collar 198. The stops 194 act to limit upward movement of the wipers 96, 98 by engagement with the brackets 192 secured to the wipers so that, as the slide 40 continues to move upwardly, the parallel links 88, 90 are swung about their pivotal connections to the brackets 74, 84, thereby imparting inward movements to the wipers. By adjusting the positions of the collars 198 on rods 20 the heightwise positions of the gaging members 196 may be varied to vary the time in the upward movement of the slide 40 when the wipers 96, 98 begin their inward movements, the members 196 being preferably so-adjusted that the beginning of the inward movement of the wipers takes place substantially at the time when the shoe and last are moved into engagement with the members 28, 30. It will be understood that the inward movement of the wipers occurs against the resistance of the light compression springs 130 until the bushings 114 engage the bushings 128, after which the comparatively heavy compression springs 118 are compressed as more particularly hereinafter explained. It will be seen also that as the wipers move toward each other they are guided in their inward movements by the stops 194 against which the brackets 192 are held by the springs 130, the compression springs 202 being of sufficient capacity to prevent upward movement of the gaging members 196 at this time. By reference to Fig. 3 it will be evident that the wipers at the beginning of their inward movements are located somewhat below the bottom face of the insole and that as they move inwardly they act to bend the margin of the upper inwardly over the bottom of the shoe without pressing it against the insole. This prevents danger of displacement of the insole and insures also against premature adherence of the upper to the insole. The heightwise positions of the wipers at the beginning of their inward movements relatively to the bottom face of the insole may be varied by vertical adjustment of the collars 198 on the rod 20.

In order that the margin of the upper will be pressed into firm adherence to the insole, the machine is provided with means for moving the stops 194 out of engagement with the brackets 192 at a predetermined time in the cycle, so as to render the stops ineffective thereafter to limit the upward movements of the wipers. For this purpose the slide 40 has secured to it blocks 206 provided with recesses into which extend the lower

end portions of rods 208 which extend upwardly in parallel relation to the rods 20. The rods 208 are pinned to the blocks 206 and pass through apertures in the collars 198 and into recesses 210 formed in the gaging members 196. Each gaging member 196 carries an adjustable set screw 212 which acts to close the upper end of the recess 210 and to serve as an adjustable stop, the construction being such that, as the rods 208 move upwardly with the slide 40, they engage the stops 212 and impart upward movements to the gaging members 196, against the resistance of the springs 202, to release the wipers 96, 98. When the wipers are released by the gaging members they are carried farther upwardly to press the margin of the upper against the insole. When the pressure is thus applied to the shoe by the wipers the resistance of the shoe to continued upward movement of the wipers causes a further swinging movement to be imparted to the parallel links 88, 90, so that the wipers are forced farther inwardly toward each other with a wiping action on the margin of the upper. The screws 212 are so adjusted that upward movements are imparted to the gaging members 196 substantially at the time when the bushings 114 engage the bushings 128 so that continued swinging movements of the parallel links 88, 90, occur against the increasing resistance of the springs 118 which act through the wipers to press the margin of the upper firmly into adhering relation to the insole.

The illustrated machine is further provided with means for conforming the shoe upper closely and tightly to the contour of the sides of the shank portion of the last and for also conforming it tightly to the contour of the forepart of the last at the rear of the toe portion before pressing its marginal portion into adhering relation to the insole along the forepart and shank portions of the shoe. As shown, this means comprises grippers for gripping the opposite side portions of the margin of the upper at the shank portion of the shoe and at the opposite sides of the forepart of the shoe, said grippers being movable with the wipers inwardly over the shoe bottom to tighten the upper over the last and to draw its marginal portion inwardly over the insole. Pivottally connected at 214 to each bracket 192 (Figs. 3, 4 and 5) are a plurality of levers 216, to which there are pivotally connected at 218 gripper jaws 220. The gripper jaws 220, herein illustrated as six in number, three at each side of the shoe, are spaced apart lengthwise of the shoe from the ball of the shoe rearwardly along its shank portion, the jaws at each side being directly opposite corresponding jaws at the other side. Each gripper jaw 220 has pivotally connected to its lower end a rod 222 which extends through an enlarged opening formed in a downwardly extending arm 224 of a bell crank lever 226 also pivoted at 214 to the bracket 192. Each lever 224 has a laterally extending arm 228 carrying a roll 230 arranged to engage the bottom face of a steel plate 232 secured to the gaging member 196. Surrounding each rod 222 is a compression spring 234 which bears at one end against a shoulder 236 on the rod and at the other end against a washer 238 provided with a concave face for engaging a convex projection 240 on the inner side face of the arm 224. A nut and lock nut 242, threaded on the end of the rod, are arranged to hold a washer 244 in engagement with the opposite side face of the arm 224 when the parts are in their idle positions (Fig. 2). When the machine is initially at rest the spring 234 is under no compression, the parts 216, 220 7

and 226 accordingly tending to swing as a unit about the axis 214 in a direction to hold the roll 230 in engagement with the plate 232. As the slide 40, however, moves upward relatively to the gaging members 196, before the members 192 engage the members 194, the levers 216 and 226 are swung in a direction to impart heightwise movement to the gripper jaw 220 relatively to the wipers 96, 98, the spring 234 acting at this time substantially as a solid member. Each lever 216 has an adjustable stop, illustrated as a screw 246, which is arranged to engage the bottom face of the wiper to limit upward swinging movement of the lever. Preferably, the stops 246 are so adjusted that only sufficient upward swinging movement will be imparted to each lever 216 to carry its associated gripper jaw 220 upwardly into position to move relatively to the wiper to clamp the marginal portion of the upper against the inner side face of the wiper without moving the gripper jaw above the upper-engaging face of the wiper. Thereafter, as the levers 226 continue to swing in the same directions the gripper jaws 220 are first swung toward the wipers about their pivotal connections 218 to the levers 216 to press the marginal portion of the upper against the inner side faces of the wipers, after which the springs 234 are compressed to cause the gripper jaws to clamp the margin of the upper hard against the wipers, the construction being such that sufficient swinging movements are imparted to the levers 226 to accomplish this before the brackets 192 are moved into engagement with the stops 194. As the wipers 96, 98 thereafter are moved toward each other from the positions shown in Fig. 3 to the positions shown in Fig. 4 by the swinging of the parallel links 88, 90, the upper is drawn tightly over the forepart and shank portions of the last by the inwardly moving gripper jaws cooperating with the wipers, the rolls 230 moving inwardly in engagement with the plates 232. It will be evident that as the wipers and grippers thus move inwardly to pull the upper, the springs 234 through which the grippers are operated to clamp the upper will permit the upper to slip between the grippers and the wipers.

Substantially at the time when the wipers 96, 98 are moved upwardly to press the margin of the upper against the insole an abutment piece 248 (Figs. 1, 2 and 4) secured to the slide 64 is arranged to be engaged by downwardly extending arms 250 carried by the levers 216 as these levers are carried inwardly with the wipers. As the wipers and grippers move inwardly from the positions shown in Fig. 4 to the positions shown in Fig. 5 the levers 216 are swung by the member 248 about their pivots 214 in directions to move the gripper jaws 220 downwardly out of engagement with the margin of the upper. By reference to Figs. 4 and 5 it will be seen that the downwardly extending arms 250 engage the abutment piece 248 substantially at the time when the rods 208 engage the adjustable screws 212 carried by the gaging members 196. As the gaging members 196 move upwardly the springs 130 act to force the wipers 94, 96 upwardly to press the margin of the upper against the insole. Since the levers 216, 226 move upwardly with the wipers there is no lowering of the gripper jaws 220 to release the margin of the upper until it has been pressed into adhering relation to the insole and the wipers have begun their inward movements to wipe and press the margin of the upper inwardly over the insole in response to resistance

of the shoe to the pressure applied. The upper is thus held under pulling strain by the wipers and gripper jaws until its marginal portion has been pressed into adherence to the insole after which the levers 216 are swung about their pivots by the abutment 248 to lower the gripper jaws. By reference to Figs. 3, 4 and 5 it will be seen that the inner side faces of the wipers 96, 98, against which the upper engaging faces of the gripper jaws are held by the springs 234, are inclined downwardly and outwardly so that as the gripper jaws are lowered from positions shown in Fig. 4 to the positions shown in Fig. 5 their upper ends are swung away from each other to prevent interference between them as the wipers move inwardly to wipe and press the margin of the upper for its entire width upon the insole. 5

In order to avoid any possibility of displacement of the marginal portion of the upper from its proper relation to the insole in the return of the wipers to their starting positions there is provided means for preventing movement of the wipers 96, 98 outwardly away from each other until after the supporting members 138 and 140 have been returned to their initial shoe-supporting positions by the springs 150 and 164. This means comprises a latch 252 mounted adjacent to each pair of opposite holders 92 and 94 and arranged to engage projections 254 on the two holders when the parts are in the positions that they assume at the end of the wiping operation and thus to prevent the holders from being returned to their starting positions by the parallel links 88, 90, and the springs 118, 130, until after the slide 40 and the parts supported thereby have been moved downwardly far enough to permit the springs 148, 164 to move the members 138, 140 upwardly to cause the projections 154, 160 on the members 138, 140 to engage the stops 156, 162 on the standards 144, 158. Each latch 252 is fast on a rockshaft 256 (Figs. 1 and 2) supported in bearings on the end of the slide 64. Each rockshaft 256 has secured to it an inwardly extending arm 258 and pivotally connected to the inner end of each arm is a rod 260 extending upwardly through an opening in a laterally extending projection 262 formed on the gaging member 196. A nut 264 on the upper end of the rod is arranged to cooperate with the projection 262 to hold the latch 252 in an idle position when the slide 40 and the parts supported thereon are in their lowest positions. As the slide 40 moves upwardly the rods 260 move relatively to the projections 262 until a compression spring 266 surrounding each rod engages the projection 262 after which, as the slide 40 continues to move upwardly, the springs 266 are compressed to swing the latches 252 into positions to catch on the projections 254 as soon as the holders 92 and 94 are lowered far enough relatively to the brackets 74, 84 to carry these projections below the latches. In the upward movements of the slide 40 and the rods 260 a sufficient movement of compression is imparted to the springs 266 to hold the latches 252 in positions to engage the projections 254 until the slide 40 has been lowered far enough to carry the wipers away from the shoe bottom and to permit the springs 148, 164 to return the supporting members 138, 140 to their initial positions. Thereafter in the lowering of the slide 70 the nuts 264 engage the projections 262 and swing the latches 252 outwardly to release the holders, whereupon the latter are returned to their starting positions by the springs 118, 130. At this time the shoe is supported by the mem- 75

bers 138, 140 so that the wipers move in their appointed paths without contacting with the overlasted margin of the upper, thus avoiding any danger of displacement of the upper by the outward movements of the wipers.

In the operation of the machine, briefly summarized, after wipers 96, 98, suitable for the style and size of shoe to be operated upon, have been mounted on the brackets 74, 84 and have 10 been heated to the desired temperature, and after proper adjustments of the brackets 74, 84 and the gages 168 have been made, the operator places a shoe bottom downward upon that pair of supporting members 138, 140, which is in its lowermost position. While the invention is not limited to the particular use illustrated, the shoe herein shown is of that type in which the marginal portion of the upper is secured in lasted position along the forepart and shank portions 20 of the shoe by an adhesive and in which an outsole is thereafter cemented to the lasted margin of the upper. In accordance with the illustrated practice, the toe and heel ends of the shoe are lasted before the side lasting operation is 25 performed, although it will be understood that so far as the present invention is concerned its utility is not dependent upon one or both of these toe and heel lasting operations having been performed before the shoe is presented to 30 the machine.

After placing a shoe in position to be operated upon, as above described, the operator starts the power operation of the machine, whereupon the slide 40 at that side of the machine where the shoe is placed, is elevated, and the slide at the other side is lowered. As the slide 40 is elevated the levers 216, 226 are swung by reason of the engagement of the rolls 230 with the stationary plates 232 as hereinbefore described, in directions to move the gripper jaws 220 upwardly until the adjustable stops 246, carried by the levers 216, engage the bottom faces of the wipers 96, 98, each screw 246 being independently adjustable to limit upward movement of its associated gripper jaw. Thereafter, as the levers 226 continue to swing in the same directions the springs 234 are operated to move the gripper jaws toward the wipers and to clamp the opposite side portions of the margin of the 45 upper against the inner side faces of the wipers. Substantially at this time in the upward movement of the slide 40 the shoe is stopped by the abutment members 28, 30 and the brackets 192 secured to the wipers engage the stops 194 on the 50 gaging members 196. Thereafter as the slide 40 continues its upward movement, the shoe-supporting members 138, 140 are depressed against the resistance of their springs 148, 164 and the holders 92 and 94 are moved toward each other 55 by the swinging of the parallel links 88, 90, about their pivotal connections to the brackets 74, 84. The wipers and grippers are thus moved inwardly and in this movement impart a pull to the upper to conform it tightly to the contour 60 of the shank portion of the last and also to conform it tightly to the curvatures of the last at the top and sides of the forepart. It will be understood that during the inward movement of the wipers and grippers to pull the upper slipping of the upper relatively to the wipers and grippers will occur if the resistance to such movement resulting from the gripping pressure of the wipers and grippers on the upper is overcome by the force of the pull applied. Such inward movement of the wipers and grippers occurs 70 75

only against the resistance of the light springs 130 which act to hold the brackets 192 in engagement with the stops 194. The stops 194 are adjusted to position the wipers at this time with their upper-engaging faces located below the bottom face of the insole so that, as the wipers move inwardly, they do not press the marginal portion of the upper upon the insole. At a predetermined time in the inward movements of the wipers and grippers and preferably at the time when they have substantially completed their upper-pulling movements the upwardly moving rods 208 engage the stops 212 and elevate the gaging members 196 to move the stops 194 out of engagement with the brackets 192, and substantially at the same time the downwardly extending arms 250 of the levers 216 engage the abutment piece 248 on the slide 64. The springs 130 then act to move the wipers upwardly to press the margin of the upper against the insole after which, as the slide 40 continues to move upwardly, further swinging movements are imparted to the parallel links 88, 90, to move the wipers farther inwardly over the insole in wiping and pressing engagement with the upper, the levers 216 being also swung about their axes 214 to lower the gripper jaws and thus to insure release of the upper by the grippers as the wipers continue their inward movements. Just after the wipers are forced up by the springs 130 to press the margin of the upper upon the insole the bushings 114 on the rods 112 engage the bushings 128. The springs 118 are accordingly compressed during the latter part of the wiping action and therefore subject the upper to increasing pressure at that time. The marginal portion of the upper is thus firmly pressed against the insole as it is wiped inwardly by the heated wipers 96, 98, which act also to iron out any surface irregularities in the upper.

The machine comes automatically to a stop with the shoe under pressure and while the shoe is held under pressure the operator presents a shoe to the other half of the machine. The shoe will be permitted to remain under pressure long enough to render the heat effective on the cement so that when the shoe is released from pressure the cement will have set firmly enough to maintain the upper securely in lasted position. When the machine is again started the latches 252 hold the wipers against outward return movements, in the downward movement of the slide 40, until the springs 148, 164 have returned the supporting members 138, 140 to their initial positions. Thereafter, the latches 252 release the holders 92 to the action of the springs 118, 130, the wipers being thus returned to their starting position without contacting with the overlasted margin of the upper or in any case without any substantial pressure on the upper.

Having described my invention, what I claim as new and desire to secure by Letters Patent of the United States is:

1. In a lasting machine, lasting means constructed and arranged to grip the marginal portion of an upper at the opposite side of a last and movable to pull the upper inwardly over an insole on the last at the opposite sides of the shoe bottom simultaneously in such spaced relation to the shoe bottom as to avoid any substantial pressure of the upper against the bottom face of the insole, mechanism for effecting relative movement of the shoe and said lasting means heightwise of the shoe to cause said means to press the upper upon the bottom face of the insole after

thus pulling it inwardly over the insole and while the upper is held under pulling strain, and mechanism for thereafter moving said lasting means farther inwardly over the insole in wiping and pressing engagement with the marginal portion of the upper.

2. In a lasting machine, wipers arranged to operate respectively at the opposite sides of a shoe between its toe and heel-end portions, members arranged to grip the marginal portion of the upper against said wipers, means for moving said wipers and gripping members to pull the upper inwardly over an insole in such spaced relation to the insole as to avoid any substantial pressure of the upper against the bottom face of the insole, means to cause said wipers to press the upper upon the bottom face of the insole after the upper has thus been pulled inwardly and while it is held under pulling strain, and means for thereafter moving said wipers farther inwardly over the insole in pressing and wiping engagement with the upper.

3. In a lasting machine, the combination with shoe-positioning means, of upper-pulling means movable inwardly over the bottom of a shoe for tightening the upper over its last and for drawing its marginal portion inwardly over an insole on the last, overlaying means movable with said upper-pulling means, and mechanism for effecting relative movement of the overlaying means and the shoe heightwise of the shoe to press the margin of the upper upon the insole after the margin of the upper has been drawn inwardly over the insole and while the upper is held under strain by said upper-pulling means, said mechanism being constructed and arranged thereafter to impart to the overlaying means a movement farther inwardly over the insole in wiping engagement with the upper.

4. In a lasting machine, the combination with shoe-positioning means, of upper-pulling means movable inwardly over the bottom of a shoe for tightening the upper over its last and for drawing its marginal portion inwardly over an insole on the last, overlaying means movable with said upper-pulling means, and mechanism for effecting relative movement of the overlaying means and the shoe heightwise of the shoe to press the margin of the upper upon the insole after the margin of the upper has been drawn inwardly over the insole and while the upper is held under strain by said upper-pulling means, said mechanism being constructed and arranged thereafter to impart to the overlaying means a movement farther inwardly over the insole in wiping engagement with the upper in response to resistance of the shoe to the pressure applied.

5. In a lasting machine, the combination with shoe-positioning means, of upper-pulling means movable inwardly over the bottom of a shoe for tightening the upper over its last and for drawing its marginal portion inwardly over an insole on the last, overlaying means movable with said upper-pulling means, a gaging device arranged for engagement with said overlaying means to determine the distance between the overlaying means and the bottom of the shoe as the upper-pulling means is moved inwardly over the insole to pull the upper and for thereafter releasing the overlaying means, and mechanism for effecting relative movement of the overlaying means and the shoe heightwise of the shoe to press the inwardly disposed margin of the upper upon the insole after the overlaying means has been released by said gaging device, said mechanism be-

ing constructed and arranged thereafter to impart to the overlaying means a further movement inwardly over the insole in wiping engagement with the upper.

6. In a lasting machine, the combination with 5 shoe-positioning means, of upper-gripping means movable inwardly over the bottom of a shoe for tightening the upper over its last and for drawing its marginal portion inwardly over an insole on the last, overlaying means movable with said upper-gripping means, a gaging device arranged by engagement with said overlaying means to determine the distance between the overlaying means and the bottom of the shoe as the upper-gripping means is moved inwardly over the insole 10 to pull the upper and for thereafter releasing the overlaying means, and mechanism for effecting relative movement of the overlaying means and the shoe heightwise of the shoe to press the inwardly disposed margin of the upper upon the 15 insole after the overlaying means has been released by said gaging device, said mechanism being constructed and arranged thereafter to impart to the overlaying means a further movement inwardly over the insole in wiping engagement 20 with the upper in response to pressure of the shoe on the overlaying means.

7. In a lasting machine, the combination with 30 shoe-positioning means, of grippers movable inwardly over the bottom of a shoe for tightening the upper over its last and for drawing the marginal portion of the upper inwardly over an insole on the last, overlaying means movable with said grippers, a gaging device arranged by engagement with said overlaying means to determine the distance between the overlaying means and the bottom of the shoe as the grippers are moved inwardly over the shoe bottom to pull the upper and for thereafter releasing the overlaying 35 means, mechanism for effecting relative movement of the overlaying means and the shoe heightwise of the shoe to press the margin of the upper upon the insole after the overlaying means has been released by said gaging device and for thereafter imparting to said overlaying means a 40 further movement inwardly over the insole in wiping engagement with the upper, and mechanism for operating the grippers to release the upper in the course of such further inward movement of the overlaying means. 50

8. In a lasting machine, the combination with shoe-positioning means, of upper-gripping means movable inwardly over the bottom of a shoe to tighten the upper over its last and to draw its marginal portion inwardly over an insole on the 55 last, overwiping means movable with said upper-gripping means, a gaging device arranged by engagement with said overwiping means to determine the distance between the overwiping means and the bottom of the shoe as the upper-gripping 60 means is moved inwardly over the shoe bottom to pull the upper, means for releasing the overwiping means from said gaging device at a predetermined time in the inward movement of the upper-gripping means, and mechanism for effecting relative 65 movement of the overwiping means and the shoe heightwise of the shoe to press the inwardly disposed margin of the upper upon the insole after the overwiping means has been released by said gaging device, said mechanism being constructed 70 and arranged thereafter to impart to the overwiping means a further movement inwardly over the shoe bottom in wiping engagement with the upper while applying progressively increasing pressure to the upper heightwise of the shoe. 75

9. In a lasting machine, the combination with shoe-positioning means, of grippers movable inwardly over the bottom of a shoe to tighten the shoe upper over its last and to draw its marginal portion inwardly over an insole on the last, overwiping means movable with said grippers, a gaging device arranged by engagement with said overwiping means to determine the position of the overwiping means heightwise of the shoe as the grippers are moved inwardly to pull the upper, means for releasing the overwiping means from said gaging device in time relation to the inward movement of the grippers, mechanism for effecting relative movement of the overwiping means and the shoe heightwise of the shoe to press the margin of the upper upon the insole after the overwiping means has been released by said gaging device, said mechanism being constructed and arranged thereafter to impart to the overwiping means a further movement inwardly over the insole in wiping engagement with the upper, and mechanism operative in response to such inward movement for operating the grippers to release the upper.
10. In a machine for lasting shoes in which the margin of the upper is secured to an insole by an adhesive, the combination with shoe-positioning means, of opposite side-lasting mechanisms comprising grippers spaced lengthwise of a shoe between the ball of the shoe and its heel-end portion and movable heightwise of the shoe into positions to grip the opposite side portions of the margin of the upper and laterally of the shoe to tighten the upper over its last and to draw its marginal portion inwardly over the insole, wipers arranged to extend lengthwise of the shoe between its toe and heel-end portions and shaped to conform substantially to the desired contour of the bottom of the shoe, said wipers being movable laterally of the shoe with the grippers, and mechanism automatically operative at a predetermined time in the movement of the grippers laterally of the shoe for effecting relative movement of the wipers and the shoe heightwise of the shoe to press the margin of the upper into adhering relation to the insole, said mechanism being constructed and arranged thereafter to impart to the wipers a further movement inwardly over the insole in wiping engagement with the upper while applying progressively increasing pressure to the upper heightwise of the shoe to force it into firm adherence to the insole.
11. In a machine for lasting shoes in which the margin of the upper is secured to an insole by an adhesive, the combination with shoe-positioning means, of heated wipers bodily movable heightwise of a shoe to press the margin of the upper into adhering relation with the insole and laterally of the shoe in wiping engagement with the margin of the upper while applying heat to hasten the setting of the adhesive, and grippers movable with said wipers for conforming the upper tightly to the curvatures of the shank portion of the last and for holding it under strain until after the margin of the upper has been pressed against the insole by said wipers.
12. In a machine for lasting shoes in which the margin of the upper is secured to an insole by an adhesive, the combination with shoe-positioning means, of heated wipers arranged to extend lengthwise of a shoe between its toe and heel-end portions and bodily movable heightwise of the shoe to press the margin of the upper along the shank and forepart of the shoe into adhering relation to the insole and laterally of the shoe in wiping engagement with the margin of the upper while applying heat to hasten the setting of the adhesive, and grippers movable with said wipers for conforming the upper tightly to the curvatures of the shank portion of the last and for holding it under strain until after the margin of the upper has been pressed against the insole by said wipers.
13. In a lasting machine, the combination with shoe-positioning means, of grippers at opposite sides of a shoe movable into positions to grip the opposite side portions of the margin of the upper and then to tighten the upper over its last and to draw its margin inwardly over an insole on the last, wipers movable with the grippers inwardly over the insole, mechanism for effecting relative movement of the wipers and the shoe heightwise of the shoe to press the margin of the upper upon the insole after the grippers have applied an inward pull to the upper, said mechanism being constructed and arranged thereafter to impart to the wipers a further movement inwardly over the insole in wiping engagement with the upper, and means for heating said wipers.
14. In a lasting machine, the combination with shoe-positioning means, of grippers at opposite sides of a shoe movable both heightwise and laterally of the shoe to grip the opposite side portions of the margin of the upper and movable to tension the upper over its last and to draw its marginal portion inwardly over the insole, wipers movable inwardly over the insole with the grippers, and means for moving the wipers relatively to the shoe heightwise of the shoe to press the margin of the upper upon the insole after the grippers have applied an inward pull to the upper, said means being constructed and arranged to impart to the wipers movements inwardly over the insole in wiping engagement with the upper in response to pressure of the shoe on the wipers.
15. In a lasting machine, the combination with shoe-positioning means, of grippers at opposite sides of a shoe movable heightwise of the shoe into positions to grip the opposite side portions of the margin of the upper and laterally of the shoe to tighten the upper over its last and to draw its margin inwardly over an insole on the last, wipers movable inwardly over the insole with said grippers, and mechanism for effecting relative movement of the wipers and the shoe heightwise of the shoe to press the margin of the upper upon the insole after the grippers have applied an inward pull to the upper, said mechanism being constructed and arranged thereafter to impart to the wipers further movement inwardly over the insole in wiping engagement with the upper while applying progressively increasing pressure to the upper heightwise of the shoe.
16. In a machine for lasting shoes in which the margin of the upper is secured to an insole by an adhesive, the combination with shoe-positioning means, of grippers at opposite sides of a shoe movable heightwise of the shoe into positions to grip the opposite side portions of the margin of the upper and laterally of the shoe to tension the upper over its last and to draw its marginal portion inwardly over the insole, heated wipers movable inwardly over the insole with the grippers, gaging devices arranged to act on said wipers to determine the distance between the wipers and the bottom face of the insole in the up-

per-pulling movements of the grippers and thereafter to release the wipers, and means effective after the wipers have been released from the gaging devices to impart to said wipers movements relatively to the shoe to wipe the margin of the upper inwardly over the insole while applying pressure to the upper heightwise of the last to force it into firm adherence to the insole and applying heat to hasten the setting of the adhesive.

17. In a lasting machine, the combination with shoe-positioning means, of a gripper for gripping the marginal portion of an upper, said gripper being movable inwardly over the bottom of the shoe to tension the upper over its last and to draw its marginal portion inwardly over an insole on the last, a wiper movable with said gripper, a gaging member arranged to act on said wiper to determine the plane of its inward movement relatively to the bottom of the shoe in the pulling of the upper and thereafter to release the wiper, mechanism effective after the wiper has been released from said gaging member to impart to said wiper movement heightwise of the shoe to press the margin of the upper upon the insole and thereafter a further movement inwardly over the insole in wiping engagement with the upper in response to resistance of the shoe to the pressure applied, and automatic means for operating the gripper to release the upper in such further inward movement of the wiper.

18. In a lasting machine, the combination with shoe-positioning means, of grippers at opposite sides of a shoe movable laterally of the shoe to tighten the upper over its last and to draw its marginal portion inwardly over an insole on the last, wipers movable with the grippers, gaging devices arranged to act on said wipers to determine the positions of the wipers heightwise of the shoe relatively to the plane of the shoe bottom during the upper-pulling movements of the grippers and thereafter to release the wipers, and mechanism effective after the wipers have been released from said gaging devices to impart to the wipers movements heightwise of the shoe to press the margin of the upper upon the insole, said mechanism being arranged to impart to the wipers movements farther inwardly over the insole in wiping engagement with the upper in response to resistance of the shoe to the pressure applied.

19. In a lasting machine, the combination with means for supporting a shoe bottom downward, of grippers for gripping the opposite side portions of the margin of the upper, said grippers being movable laterally of the shoe to tighten the upper over its last and to draw its margin inwardly over an insole on the last, wipers movable over the insole with said grippers, and means for imparting to the wipers upper-pressing movements heightwise of the shoe and further inward wiping movements while applying progressively increasing pressure to the upper after the grippers have applied an inward pull to the upper.

20. In a lasting machine, a combination with means for supporting a shoe bottom downward, of grippers movable to pull the upper inwardly over an insole, wipers movable inwardly over the insole with the grippers and also movable upwardly to press the marginal portion of the upper upon the insole, and gaging devices constructed and arranged to limit upward movement of the wipers while permitting them to move inwardly and for releasing them for further upward move-

ment after the grippers have applied an inward pull to the upper.

21. In a lasting machine, the combination with means for supporting a shoe bottom downward, of grippers for gripping the upper at opposite sides of the shoe and movable laterally of the shoe to tighten the upper over its last and to draw its margin inwardly over an insole on the last, wipers for laying the marginal portion of the upper inwardly over the insole, means for 10 moving the wipers heightwise of the shoe to press the margin of the upper upon the insole and for also moving them inwardly over the insole in wiping engagement with the upper, and means arranged to cooperate with said last-named means 15 to determine the heightwise positions of the wipers relatively to the bottom of the shoe until after the grippers have applied an inward pull to the upper.

22. In a lasting machine, the combination with 20 means for supporting a shoe bottom downward, of grippers for gripping the opposite side portions of the margin of the upper and movable laterally of the shoe to tighten the upper over its last and to draw its marginal portion inwardly 25 over an insole on the last, wipers for wiping the marginal portion of the upper inwardly over the insole and for pressing it upon the insole, means for imparting to the wipers movement heightwise of the shoe to press the upper upon the insole 30 and for also moving them inwardly over the insole in wiping engagement with the upper, and means for limiting such movement of the wipers heightwise of the shoe after the beginning of the movement and for releasing them only after the 35 grippers have applied an inward pull to the upper.

23. In a lasting machine, the combination with means for supporting a shoe bottom downward, of grippers for gripping the opposite side portions of the margin of the upper and movable laterally 40 of the shoe to pull the upper over its last and to draw its marginal portion inwardly over an insole on the last, wipers for wiping the margin of the upper inwardly over the insole and for pressing it up against the insole, means for moving the wipers upward to press the margin of the upper upon the insole and for also moving them inwardly in wiping engagement with the margin of the upper, gaging devices arranged to act on said wipers to determine their positions 50 heightwise of the shoe relatively to the bottom face of the insole, and means for releasing the wipers from the gaging devices to permit them to be moved farther upward after the grippers have applied an inward pull to the upper. 55

24. In a lasting machine, the combination with means for supporting a shoe bottom downward, of grippers for gripping the opposite side portions of the margin of the upper and movable laterally 60 of the shoe to pull the upper over its last and to draw its marginal portion inwardly over an insole on the last, wipers for wiping the margin of the upper at the opposite sides of the shoe inwardly over the insole and for pressing it up against the 65 insole, wiper-operating means for imparting to the wipers upward movements to press the upper upon the insole and for also moving them inwardly over the insole in wiping engagement with the margin of the upper, gaging devices 70 arranged to act on said wipers to determine the distance between the wipers and the bottom face of the insole, and means controlled by said wiper-operating means for releasing the wipers from said gaging devices to permit them to be moved 75

farther upwardly in time relation to the inward movements of the grippers.

25. In a lasting machine, the combination with means for supporting a shoe bottom downward, of grippers for gripping and pulling the upper over its last and for drawing its marginal portion inwardly over an insole on the last, wipers for wiping the margin of the upper inwardly over the insole and for pressing it up against the insole, 10 wiper-operating means for imparting to said wipers movements heightwise of the shoe and for also moving them inwardly over the shoe bottom, gaging members adjustable heightwise of the shoe and arranged to act on said wipers to 15 determine the distance between the wipers and the bottom face of the insole, and means for releasing the wipers from said gaging members to permit them to be moved farther upwardly at a predetermined time in the inward movement 20 of the grippers.
26. In a lasting machine, the combination with means for supporting a shoe bottom downward, of grippers movable both heightwise and laterally of the shoe to grip and pull the upper over its 25 last and to draw its marginal portion inwardly over an insole on the last, wipers for wiping the margin of the upper inwardly over the insole, wiper-operating means for moving the wipers heightwise of the shoe to press the margin of the 30 upper upon the insole and for also moving them inwardly over the insole, gaging members for limiting the movements of the wipers heightwise of the shoe and for determining the plane of their inward movements relatively to the bottom of the 35 shoe, and means controlled by said wiper-operating means for imparting to said gaging members at a predetermined time in the inward movements of the grippers a movement heightwise of the shoe to permit the wipers to complete their inward movements closer to the plane of the shoe bottom.

27. In a machine for shaping uppers over lasts, the combination with shoe-supporting means, of overlaying means movable inwardly over the 45 bottom of a shoe to lay the margin of the upper over an insole, a gaging device arranged by engagement with said overlaying means to determine its position heightwise of the shoe relatively to the plane of the shoe bottom, means for moving the overlaying means heightwise of the shoe to press the margin of the upper upon the insole, and means for releasing said overlaying means from said gaging device to permit such movement.

28. In a lasting machine, wipers movable bodily 55 widthwise of a shoe to wipe the marginal portion of the upper inwardly over the shoe bottom at the opposite sides of the shoe simultaneously, means for moving said wipers substantially as far inwardly as the edge of the upper in wiping engagement with the upper, means for heating said wipers, and members arranged to clamp the marginal portion of the upper against said wipers for applying an inward pull to the upper as the wipers receive their inward movements.

29. In a lasting machine, wipers of substantially rigid material arranged to engage the marginal portion of an upper at the opposite sides of a shoe and movable bodily widthwise of the shoe to wipe the upper inwardly over the shoe bottom at 65 the opposite sides simultaneously, means for heating said wipers, and means movable with said wipers for clamping the marginal portion of the upper against the wipers and for applying an inward pull to the upper during a portion only of 70 the inward wiping movements of the wipers.

30. In a lasting machine, wipers movable bodily widthwise of a shoe to wipe the marginal portion of the upper inwardly over the shoe bottom at the opposite sides of the shoe simultaneously, members arranged to clamp the marginal portion of the upper against said wipers and movable with the wipers to apply to the upper an inward pull over the shoe bottom, and automatic means for operating said members to clamp the upper before the wipers begin their inward movements and for thereafter releasing them from the upper at a predetermined time prior to the completion of the inward movements of the wipers.

31. In a lasting machine, wipers movable bodily widthwise of a shoe to wipe the marginal portion of the upper inwardly over the shoe bottom at the opposite sides of the shoe simultaneously, members arranged to clamp the marginal portion of the upper against said wipers for applying an inward pull to the upper as the wipers receive their inward movements, and mechanism for moving said members first heightwise of the shoe toward the shoe bottom and then outwardly toward the wipers to clamp the upper against the wipers.

32. In a lasting machine, the combination with shoe-positioning means, of wipers for wiping the marginal portion of the upper at the opposite sides of a shoe inwardly over the shoe bottom, a wiper support mounted for movement to carry the wipers in a direction heightwise of the shoe before they begin their wiping movements, members arranged to clamp the marginal portion of the upper against the wipers for applying an inward pull to the upper in the inward movements of the wipers, and mechanism arranged to be operated by said movement of the wiper support to move said members into upper-clamping positions.

33. In a lasting machine, the combination with shoe-positioning means, of wipers for wiping the marginal portion of the upper at the opposite sides of a shoe inwardly over the shoe bottom, a wiper support mounted for movement to carry the wipers in a direction heightwise of the shoe before they begin their wiping movements, members arranged to clamp the marginal portion of the upper against the wipers for applying an inward pull to the upper in the inward movements of the wipers, and mechanism arranged to be operated by said movement of the wiper support to move said members first heightwise of the shoe toward the shoe bottom and then outwardly toward the wipers to clamp the upper against the wipers.

34. In a lasting machine, wipers movable widthwise of a shoe to wipe the marginal portion of the upper at the opposite sides of the shoe inwardly over the shoe bottom, members arranged to clamp the marginal portion of the upper against said wipers with said marginal portion extending heightwise of the shoe, said members being movable with the wipers to apply an inward pull to the upper as the wipers receive their inward movements, and automatic means for moving said members relatively to the wipers heightwise of the shoe away from the shoe bottom at a predetermined time in the inward movements of the wipers.

35. In a lasting machine, wipers movable widthwise of a shoe to wipe the marginal portion of the upper at the opposite sides of the shoe inwardly over the shoe bottom, members arranged to clamp the marginal portion of the upper against said wipers with said marginal portion extending heightwise of the shoe, said members being mov-

able with the wipers to apply an inward pull to the upper as the wipers receive their inward movements, and mechanism operative in response to the inward movements of the wipers to move said members relatively to the wipers heightwise of the shoe away from the shoe bottom.

36. In a lasting machine, wipers movable widthwise of a shoe to wipe the marginal portion of the upper at the opposite sides of the shoe inwardly over the shoe bottom, members arranged to clamp the marginal portion of the upper against said wipers with said marginal portion extending heightwise of the shoe, said members being movable with the wipers to apply an inward pull to the upper as the wipers receive their inward movements, bell crank levers controlling said members, and relatively stationary means arranged to act on said bell crank levers to move said members in directions heightwise of the shoe away from the shoe bottom at a predetermined time in the inward movements of the wipers.

37. In a lasting machine, wipers movable bodily widthwise of a shoe to wipe the marginal portion of the upper inwardly over an insole at the opposite sides of the shoe simultaneously, members movable with said wipers for applying to the upper an inward pull over the insole as the upper is wiped inwardly over the wipers, and automatic means to cause the wipers to operate with a substantial amount of clearance between them and the insole until the upper has been subjected to such an inward pull and thereafter to operate with less clearance between them and the insole in their further inward movements.

38. In a lasting machine, wipers movable bodily widthwise of a shoe to wipe the marginal portion of the upper inwardly over an insole at the opposite sides of the shoe simultaneously, members arranged to clamp the marginal portion of the upper against said wipers and movable with the wipers for applying to the upper an inward pull over the insole as the upper is wiped inwardly by the wipers, and automatic means to cause the wipers in their initial inward movements to operate with a substantial amount of clearance between them and the insole and thereafter to operate with less clearance between them and the insole on their further inward movements.

39. In a lasting machine, wipers movable bodily widthwise of a shoe to wipe the marginal portion of the upper at the opposite sides of the shoe inwardly over the shoe bottom, wiper-supporting means movable heightwise of the shoe, mechanism carried by said wiper-supporting means for moving the wipers inwardly widthwise of the shoe in response to resistance to their movements heightwise of the shoe, and controlling means arranged to resist said last-named movements of the wipers to render said mechanism operative to move them inwardly, said controlling means being so positioned as to cause the wipers to operate initially with a substantial amount of clearance between them and the shoe bottom and being thereafter displaceable to permit the wipers to operate in closer relation to the shoe bottom in their further inward movements.

40. In a lasting machine, wipers movable bodily widthwise of a shoe to wipe the marginal portion of the upper at the opposite sides of the shoe inwardly over the shoe bottom, wiper-supporting means movable heightwise of the shoe, mechanism carried by said wiper-supporting means for moving the wipers inwardly widthwise of the shoe in response to resistance to their movements heightwise of the shoe, controlling means arranged to

resist said last-named movements of the wipers to render said mechanism operative to move them inwardly, said controlling means being so positioned as to cause the wipers to operate initially with a substantial amount of clearance between them and the shoe bottom and being thereafter displaceable to permit the wipers to approach the shoe bottom, and spring means for forcing the wipers toward the shoe bottom when said controlling means is thus displaced.

41. In a lasting machine, wipers movable bodily widthwise of a shoe to wipe the marginal portion of the upper at the opposite sides of the shoe inwardly over the shoe bottom, wiper-supporting means movable heightwise of the shoe, mechanism carried by said wiper-supporting means for moving the wipers inwardly widthwise of the shoe in response to resistance to their movements heightwise of the shoe, controlling means arranged to resist said last-named movements of the wipers to render said mechanism operative to move them inwardly, said controlling means being so positioned as to cause the wipers to operate initially with a substantial amount of clearance between them and the shoe bottom, mechanism arranged to be operated by movement of said wiper-supporting means to displace said controlling means from its normal position and thus to permit the wipers to approach closer to the shoe bottom, and spring means for forcing the wipers toward the shoe bottom when said controlling means is thus displaced.

42. In a lasting machine, wipers movable bodily widthwise of a shoe to wipe the marginal portion of the upper at the opposite sides of the shoe inwardly over the shoe bottom, wiper-supporting means movable heightwise of the shoe, swinging links carried by said wiper-supporting means for moving the wipers inwardly widthwise of the shoe in response to resistance to their movements heightwise of the shoe, spring means arranged to be subjected to stress by the swinging of said links, controlling means arranged to resist movements of the wipers heightwise of the shoe and thus to render said links operative to move them inwardly, and means for displacing said controlling means from its normal position after a predetermined amount of inward movement of the wipers to permit them to be forced into closer relation to the shoe bottom by said spring means.

43. In a machine for shaping uppers over lasts, the combination with shoe-positioning means, of a wiper movable inwardly over the bottom of a shoe to lay the margin of the upper over an insole, a gaging member arranged to act on said wiper to determine the distance between the wiper and the bottom face of the insole and to prevent the wiper from increasing its pressure on the margin of the upper, means for moving the wiper heightwise of the shoe to press the margin of the upper upon the insole, and mechanism controlled by said last-named means for moving the gaging member relatively to the wiper to permit such pressing movement.

44. In a machine for shaping uppers over lasts, the combination with shoe-positioning means, of wipers arranged to extend lengthwise of a shoe between its toe and heel-end portions and shaped to conform substantially to the curvatures of the opposite side edges of an insole, gaging devices arranged to act on said wipers to determine their positions heightwise of the shoe relatively to the bottom face of the insole, operating means for moving said wipers heightwise of the shoe into

the positions determined by said gaging devices and for thereafter moving them inwardly over the insole, and means for releasing the wipers from said gaging devices at a predetermined time 5 in the inward movement of the wipers to permit said operating means to move the wipers farther heightwise of the shoe to press the margin of the upper upon the insole.

45. In a machine for shaping uppers over lasts, 10 the combination with shoe-positioning means, of wipers arranged to extend lengthwise of a shoe between its toe and heel-end portions and shaped to conform substantially to the curvatures of the opposite side edges of an insole, gaging members 15 arranged to act on said wipers to determine their positions heightwise of the shoe relatively to the bottom face of the insole, means for moving said wipers heightwise of the shoe into the positions determined by said gaging members and for 20 thereafter moving them inwardly over the insole including springs arranged to be tensioned in the inward movements of the wipers and tending to move them heightwise of the shoe, and means for operating the gaging members to release 25 the wipers to the action of said springs at a predetermined time in the inward movement of the wipers.

46. In a machine for shaping uppers over lasts, 30 the combination with shoe-positioning means, of wipers arranged to extend lengthwise of a shoe between its toe and heel-end portions for laying the marginal portion of the upper along the forepart and shank portions of the shoe inwardly over an insole, gaging devices arranged to act on 35 said wipers to determine the positions of the wipers heightwise of the shoe relatively to the bottom face of the insole during a portion of their inward movements and for releasing them in time relation to their inward movements, and 40 mechanism for moving the wipers heightwise of the shoe into the positions determined by said gaging devices and for also moving them inwardly over the insole, said mechanism being constructed and arranged to impart to the wipers 45 movements farther inwardly over the insole in wiping engagement with the upper and to move them also toward the insole after the wipers have been released by the gaging devices.

47. In a machine for shaping uppers over 50 lasts, the combination with shoe-positioning means, of wipers arranged to extend lengthwise of a shoe between its toe and heel-end portions and shaped to conform substantially to the curvatures of the opposite side edges of an insole, gaging members 55 arranged to act on said wipers to determine their positions heightwise of the shoe relatively to the bottom face of the insole, means for moving said wipers heightwise of the shoe into the positions determined by said gaging members and for thereafter moving them inwardly over the insole, spring means against the 60 resistance of which the wipers are thus movable inwardly over the insole, said spring means tending to move the wipers heightwise of the shoe, 65 and means for imparting to said gaging members at a predetermined time in the inward movement of the wipers movements in a direction heightwise of the shoe to permit said spring means to force the wipers farther toward the 70 insole to apply increased pressure to the margin of the upper.

48. In a lasting machine, the combination 75 with shoe-positioning means, of wipers at opposite sides of a shoe for laying the marginal portion of the upper inwardly over an insole, said

wipers being mounted for positioning movements heightwise of the shoe, grippers movable with said wipers inwardly over the insole for tensioning the upper over its last and for drawing its marginal portion over the insole, and mechanism for operating the grippers to grip the opposite side portions of the margin of the upper in response to movement of the wipers heightwise of the shoe.

49. In a lasting machine, the combination 10 with shoe-positioning means, of wipers at opposite sides of a shoe for laying the marginal portion of the upper inwardly over an insole, said wipers being mounted for positioning movements heightwise of the shoe, grippers movable with 15 said wipers inwardly over the insole for tensioning the upper over its last and for drawing its marginal portion over the insole, and mechanism for operating the grippers to grip the opposite side portions of the margin of the upper in response to movement of the wipers heightwise of the shoe and for thereafter releasing them from the upper at a predetermined time in the inward movement of the wipers.

50. In a lasting machine, the combination 20 with shoe-positioning means, of wipers at opposite sides of a shoe for laying the marginal portion of the upper inwardly over an insole, said wipers being mounted also for positioning movements heightwise of the shoe, gripper jaws 30 movable with said wipers and arranged to cooperate therewith to tighten the upper over its last and to draw its marginal portion inwardly over the insole, and mechanism operative in response to relative movement of the wipers and the shoe heightwise of the shoe to impart to said gripper jaws movements heightwise of the shoe and thereafter movements laterally of the shoe to clamp the opposite side portions of the margin of the upper against the wipers before the 40 wipers begin their inward movements.

51. In a lasting machine, the combination with shoe-positioning means, of wipers at opposite sides of a shoe for laying the marginal portion of the upper inwardly over an insole, said wipers being mounted for positioning movements heightwise of the shoe, gripper jaws movable relatively to the wipers in the course of their positioning movements for clamping the opposite side portions of the upper against the wipers, 55 said gripper jaws being movable thereafter with the wipers to tighten the upper over its last and to draw its margin inwardly over the insole, and mechanism operative in response to inward movements of the wipers for moving the gripper jaws relatively to the wipers to release the upper.

52. In a lasting machine, the combination with shoe-positioning means, of wipers at opposite sides of a shoe for laying the marginal portion 60 of the upper inwardly over an insole, said wipers being mounted for positioning movements heightwise of the shoe, gripper jaws movable with said wipers and arranged to cooperate therewith to tighten the upper over its last and to draw its marginal portion inwardly over the insole, mechanism operative in response to movement of the wipers heightwise of the shoe to impart to said gripper jaws movements heightwise of the shoe relatively to the wipers and thereafter movements laterally of the shoe 70 relatively to the wipers to clamp the opposite side portions of the margin of the upper against the wipers before the wipers begin their inward movement, and means for operating said mechanism to lower the gripper jaws to release the 75

upper at a predetermined time in the inward movements of the wipers.

53. In a lasting machine, lasting devices for use at opposite sides of a shoe comprising wipers arranged to extend along the shank and the forepart of the shoe and movable laterally of the shoe to wipe the marginal portion of the upper inwardly over an insole and grippers arranged to grip the opposite side portions of the margin of the upper between the ball of the shoe and its heel-end portion and movable with the wipers to conform the upper tightly to the contour of the shank portion of its last and also to conform it tightly to the curvatures of the last at the top and sides of the forepart, said grippers being arranged to release the upper at a predetermined time in the inward movements of the wipers, gaging devices arranged by engagement with said wipers to determine the distance between the bottom face of the insole and the wipers during the upper-pulling movements of the grippers and for thereafter releasing the wipers, and means for effecting relative movement of the wipers and the shoe heightwise of the shoe to press the margin of the upper against the insole after the wipers have been released by said gaging devices and before the upper is released by the grippers.

54. In a lasting machine, lasting devices for use at opposite sides of a last for tensioning an upper over the last and for wiping and pressing its marginal portion inwardly over an insole on the last, comprising wipers arranged to extend along the sides of the last between its toe and heel-end portions and shaped to conform substantially to the curvatures of the opposite side edges of the insole and gripper jaws carried by said wipers, mechanism for moving the wipers and the gripper jaws heightwise of the shoe and for also moving them inwardly over the insole, and mechanism operative in response to such heightwise movement for moving the gripper jaws relatively to the wipers to grip the opposite side portions of the margin of the upper, said last-named mechanism being constructed and arranged thereafter to impart to the gripper jaws movements relatively to the wipers to release the upper in time relation to the inward movements of the wipers.

55. In a lasting machine, lasting devices for use at opposite sides of a shoe for tensioning the upper over its last and for wiping and pressing its marginal portion inwardly over an insole on the last, comprising wipers arranged to extend lengthwise of the shoe between its toe and heel-end portions and shaped to conform substantially to the desired curvatures of the bottom of the shoe and gripper jaws carried by said wipers and spaced lengthwise thereof along the shank portion of the shoe and at the opposite sides of the ball of the shoe, mechanism for moving said wipers heightwise of the shoe and for also moving them inwardly over the insole including springs for yieldingly opposing the inward movements of the wipers, gaging devices arranged by engagement with said wipers to determine their positions heightwise of the shoe relatively to the bottom of the shoe and for releasing them to the action of said springs at a predetermined time in their inward movements, and mechanism operative in response to movement of the wipers heightwise of the shoe for moving the gripper jaws relatively to the wipers to clamp the opposite side portions of the margin of the upper against the wipers, said mechanism being ar-

ranged to impart to the gripper jaws movements relatively to the wipers to release the upper after the wipers have been released by said gaging devices.

56. In a lasting machine, the combination with shoe-positioning means, of wipers at opposite sides of a shoe movable inwardly over the shoe bottom for laying the marginal portion of the upper inwardly over an insole along the forepart and shank portions of the shoe, said wipers being mounted also for positioning movements heightwise of the shoe, gripper jaws movable with said wipers and arranged to cooperate therewith to tighten the upper over its last and to draw its marginal portion inwardly over the insole, mechanism operative in response to relative movement of the wipers and the shoe heightwise of the shoe to move said gripper jaws relatively to the wipers to clamp the opposite side portions of the margin of the upper against the wipers, said mechanism being arranged thereafter to move the gripper jaws relatively to the wipers to release the upper in time relation to the inward movements of the wipers.

57. In a lasting machine, the combination with shoe-positioning means, of wipers at opposite sides of a shoe for laying the marginal portion of the upper inwardly over an insole along the forepart and shank portions of the shoe, said wipers being mounted for positioning movements heightwise of the shoe, gripper jaws movable inwardly over the insole with said wipers for tensioning the upper over its last and for drawing its marginal portion over the insole, and mechanism for swinging said gripper jaws about different axes to move them heightwise and laterally of the shoe respectively into positions to clamp the opposite side portions of the margin of the upper against the wipers before the wipers begin their inward movements.

58. In a lasting machine, the combination with shoe-positioning means, of wipers at opposite sides of a shoe for laying the marginal portion of the upper inwardly over an insole along the forepart and shank portions of the shoe, said wipers being mounted for positioning movements heightwise of the shoe, gripper jaws movable inwardly over the insole with said wipers for tensioning the upper over its last and for drawing its marginal portion over the insole, mechanism for swinging the gripper jaws relatively to the wipers heightwise and laterally of the shoe to clamp the opposite side portions of the margin of the upper against the wipers before the wipers begin their inward movements, and adjustable means for limiting the swinging movements of the gripper jaws heightwise of the shoe.

59. In a lasting machine, the combination with shoe-positioning means, of wipers at opposite sides of a shoe for laying the marginal portion of the upper inwardly over an insole along the forepart and shank portions of the shoe, said wipers being mounted for positioning movements heightwise of the shoe, a plurality of gripper jaws movable with said wipers and arranged to cooperate therewith to tension the upper over its last and to draw its marginal portion inwardly over the insole, and a plurality of devices operative in response to movement of the wipers heightwise of the shoe for moving the respective gripper jaws heightwise of the shoe relatively to the wipers and then laterally of the shoe to clamp the opposite side portions of the margin of the upper against the wipers, each of said devices including a member independently adjustable to

limit movement of the gripper jaw heightwise of the shoe.

60. In a lasting machine, the combination with shoe-positioning means, of wipers at opposite sides of a shoe movable inwardly over the bottom of the shoe for laying the margin of the upper along the forepart and shank portions of the shoe over the insole, said wipers being mounted also for positioning movements heightwise of the shoe, gripper jaws movable relatively to said wipers during their movements heightwise of the shoe for clamping the margin of the upper along the opposite sides of the shank portion of the shoe against the wipers, said gripper jaws being movable thereafter with the wipers to tension the upper over its last and to conform it tightly to the curvatures of the shank portion of the last, and mechanism for operating the gripper jaws to release the upper at a predetermined time in the inward movements of the wipers.

61. In a lasting machine, the combination with shoe-positioning means, of wipers arranged to extend lengthwise of a shoe between its toe and heel-end portions and shaped to conform to the desired contour of the bottom of the shoe, mechanism for effecting relative movement of the wipers and the shoe heightwise of the shoe and for also moving them inwardly over the shoe bottom, gaging devices arranged by engagement with said wipers to determine their positions heightwise of the shoe, means for releasing the wipers from the gaging devices at a predetermined time in the inward movements of the wipers, gripper jaws movable with said wipers, and automatic means for imparting to said gripper jaws movements relatively to the wipers to clamp the opposite side portions of the margin of the upper against the wipers before the wipers begin their inward movements and to release the upper only after the wipers have been released from said gaging devices.

62. In a machine for shaping uppers over lasts, the combination with shoe-supporting means, of a wiper, a support for said wiper movable toward and from the shoe, connections between said wiper and its support for moving the wiper relatively to the shoe to lay the margin of the upper inwardly over the shoe bottom in response to relative movement of the wiper and its support, and a member arranged to act on the wiper to limit its movement toward the shoe and thereby to determine the time in the movement of the support toward the shoe when the wiper begins its inward movement.

63. In a machine for shaping uppers over lasts, the combination with shoe-positioning means, of a wiper, a support for said wiper movable toward and from the shoe, connections between said wiper and its support for moving the wiper inwardly over the shoe bottom in response to relative movement of the wiper and its support, and a member arranged by engagement with said wiper to limit its movement toward the shoe and thereby to determine the time in the movement of the support toward the shoe when the wiper begins its inward movement, said member being adjustable heightwise of the shoe to determine the distance between the wiper and the bottom of the shoe.

64. In a machine for shaping uppers over lasts, the combination with shoe-positioning means,

of a wiper, a support for said wiper movable toward and from the shoe, connections between said wiper and its support for moving the wiper inwardly over the shoe bottom in response to relative movement of the wiper and its support including springs arranged to be tensioned by said relative movement, a stop arranged by engagement with the wiper to limit its movement toward the shoe and thereby to cause said connections to impart to the wiper its inward movement, and means movable with the support for moving the stop out of engagement with the wiper at a predetermined time in its inward movement to permit the springs to force the wiper toward the shoe to press the margin of the upper against the insole, said connections being arranged thereafter to impart to the wiper a further movement inwardly over the shoe bottom in wiping engagement with the upper in response to continued movement of the support toward the shoe.

65. In a lasting machine, wipers, a support for moving said wipers heightwise of a shoe to press the margin of an upper upon an insole including members arranged to support the shoe initially bottom downward with its bottom face above said wipers, said members being yieldable to permit the wipers to engage the bottom of the shoe, connections between said wiper support and the wipers for moving them inwardly over the shoe bottom, spring means for yieldingly opposing the inward movements of the wipers and for thereafter moving them outwardly, and means for holding the wipers against outward return movement until after the shoe-supporting members have moved the shoe above the wipers.

66. In a lasting machine, wipers, a support for moving said wipers heightwise of a shoe to press the margin of the upper upon an insole including members arranged to support the shoe initially bottom downward with its bottom face above said wipers, said members being yieldable to permit the wipers to press on the bottom of the shoe, spring means for yieldingly opposing the inward movements of the wipers and for thereafter moving them outwardly, mechanism for preventing the outward return movement of the wipers, and means to cause said mechanism to release the wipers after the shoe has been moved above the wipers by said shoe-supporting members.

67. In a lasting machine, wipers, a support for moving said wipers heightwise of a shoe to press the margin of an upper upon an insole including members arranged to support the shoe initially bottom downward with its bottom face above said wipers, said members being yieldable to permit the wipers to engage the bottom of the shoe, connections between said wiper support and the wipers for moving them inwardly over the shoe bottom in response to pressure of the shoe against the wipers, spring means for yieldingly opposing the inward movements of the wipers and for thereafter moving them outwardly, latch mechanism for preventing outward return movement of the wipers, and means to cause the latch mechanism to release the wipers after the shoe has been moved above the wipers by said supporting members.

CERTIFICATE OF CORRECTION.

Patent No. 2,041,955.

May 26, 1936.

CHARLES F. PYM.

It is hereby certified that error appears in the printed specification of the above numbered patent requiring correction as follows: Page 11, first column, line 28, claim 37, for the word "over" read by; and that the said Letters Patent should be read with this correction therein that the same may conform to the record of the case in the Patent Office.

Signed and sealed this 8th day of September, A. D. 1936.

Leslie Frazer

(Seal)

Acting Commissioner of Patents.
